Primary Examiner — Barbara Fox*Assistant Examiner* — Jamaal Rasheed(74) *Attorney, Agent, or Firm* — Nirav D. Parikh; Edgar A. Zarins(57) **CLAIM**

The ornamental design for a faucet, as shown and described.

DESCRIPTION

FIG. 1 is a front perspective view of a faucet showing my new design;

FIG. 2 is a rear perspective view thereof;

FIG. 3 is a top plan view thereof;

FIG. 4 is a left side view thereof;

FIG. 5 is a rear view thereof;

FIG. 6 is a right side view thereof;

FIG. 7 is a front elevational view thereof; and,

FIG. 8 is a bottom view thereof.

The broken-line disclosure in the view represents a portion of the faucet in which the claimed design is embodied, but which forms no part of the claimed design.

1 Claim, 3 Drawing Sheets(56)
